FURNITURE DRAWER LOCK

James C. Siegel, New York, N. Y.

Application November 2, 1939, Serial No. 302,514

7 Claims. (Cl. 45—94)

This invention relates to drawer locking mechanism of the type described in my Patent No. 2,182,504, issued December 5, 1939, for a Furniture drawer lock.

As is explained in the said patent, drawer locking mechanism for locking simultaneously a group of drawers in an article of furniture, has for many years been considered desirable. Because furniture equipped with drawers is made by many different manufacturers, and because each manufacturer may have many different styles and sizes, it has been impossible heretofore to equip furniture with locking mechanism, unless this locking mechanism was especially designed for each particular style of furniture and for each particular size thereof. Naturally, such specially designed locking mechanism was high in cost and not available for popular priced furniture. My patent discloses locking mechanism for furniture which may be manufactured in large quantities and readily applied to furniture of many different styles and sizes. Because of this adaptation of my invention to furniture manufactured under modern systems of mass production, my invention has attained considerable commercial success.

The invention disclosed and claimed by me in this application is an improvement on that shown in my patent supra. In this application, I shall show devices which facilitate further the installation of locking mechanism in furniture of different styles and different sizes.

For a description of my invention, I shall refer to Fig. 1 which shows the back of a piece of furniture equipped with sliding drawers. Fig. 2 is a perspective view of a bracket utilized in Fig. 1. Fig. 3 is a view showing the assembly of the bracket to a locking bar. Fig. 4 is a view looking down on one of the drawer locking hooks, while Fig. 5 is a perspective view of a locking hook.

Referring now more particularly to the drawing, reference numeral 10 indicates part of an article of furniture such as a bureau, desk, chiffonier, etc., having drawers 11 and 12 supported and separated by partitions 13 and 14. The locking mechanism of my invention includes a locking bar assembly 15 which comprises a horizontal arm 16 and a vertical arm 17 connected by a reinforcing angular bar 18.

A locking cylinder of the type shown in my patent supra, the construction of which is well known in the art, is designated by reference numeral 19, and an extension 20 thereof is secured as at 21 to the horizontal arm 16. The vertical

arm 17 operates in slots 22 of the partitions 13 and 14, as is best seen in Fig. 4, and is maintained in the said slots by metal plates 23 held in place by screws 24.

A unique type of bracket 25, shown best in Figs. 2 and 3, is utilized by me for supporting for sliding movement the locking bar 15 through cooperation with the horizontal arm 16 thereof. The bracket 25 is equipped with a bearing portion 26 having a constricted entrance defined by surfaces 27 and 28. In applying the locking mechanism to an article of furniture, the horizontal arm 16 is first inserted into each of the bearing slots 26 of a suitable number of brackets. Once inserted into the bearing slots, in a manner illustrated best in Fig. 3, arm 16 is maintained in those bearing slots for sliding movement in a plane juxtaposed to the backs of the several drawers. The brackets 25 are suitably secured, as illustrated on the partition 13, in positions best suited for the particular installation. It is only by manipulation of arm 16 relatively to the brackets 25, opposite to that in assembling arm 16 to the brackets illustrated in Fig. 3, that it is possible to move arm 16 out of the several bracket slots.

For locking each of the drawers, I utilize a hook 29, shown best in Figs. 4 and 5, this hook being secured in Fig. 4 to the drawer 12. It is readily seen that when the locking bar 15 is moved to the right from the position of Fig. 1, the vertical arm 17 will move into locking relation with hooks 29 to prevent outward movement of the drawers 11 and 12.

It is well to note that the reinforcing bar 18 of the locking bar assembly is spring actuated by a spring 30 relatively to one of the brackets 25 through the fastening of the end of the spring 30 to the small bore 31 in the bracket 25. When the locking cylinder is operated to release the locking bar assembly 15, the spring 30 will move the bar to the left and to the release position of Fig. 1.

Considering now the invention in its entirety, it is readily perceived that a manufacturer wishing to apply my mechanism to his furniture, may do so by buying a suitable number of brackets 25, hooks 24, and plates 23. By merely notching the partitions of his furniture so as to apply the plates 23 thereto, and by securing the brackets 25 and hooks 24 in any particular position which he may desire, he may readily assemble the entire locking mechanism in a very few minutes. Cylinder lock 19 is, of course, quite easily applied.

Those skilled in the art will now appreciate that through the contribution which I have made and herein described, the application of my locking mechanism to an article of furniture is greatly facilitated, and that the application of the locking mechanism may be made to practically any article of furniture without the manufacture of special parts of special size.

I now claim:

1. In a combination of the class described, a cabinet housing having a series of sliding drawers, partitions between said drawers, a series of brackets supported on one of said partitions, each of said brackets having a bearing slot internally thereof and a constricted entrance into said bearing slot, a locking bar having a horizontal arm, said horizontal arm entering said bearing slots through said constricted entrances and thereafter maintained in said bearing slots for horizontal sliding movement, the plane of said sliding movement being juxtaposed to the plane of the backs of said drawers, means whereby said bar locks said drawers in one position of said bar, and means for locking said bar against movement from said one position.

2. In a combination of the class described, a cabinet housing having a series of sliding drawers, partitions between said drawers, a series of brackets having flanges whereby to be secured on one of said partitions with a portion of each of said brackets extending vertically from said partition, each of said bracket portions having a bearing slot internally thereof and a constricted entrance into said bearing slot, a locking bar having a horizontal arm, said horizontal arm entering said bearing slots through said constricted entrances and thereafter maintained in said bearing slots for horizontal sliding movement, the plane of said sliding movement being juxtaposed to the plane of the backs of said drawers, means whereby said bar locks said drawers in one position of said bar, and means for locking said bar against movement from said one position.

3. In a combination of the class described, a cabinet housing having a series of sliding drawers, partitions between said drawers, a locking bar having a horizontal arm, a series of brackets having flanges whereby to be fixed to one of said partitions with a portion of each of said brackets extending vertically from said partition and substantially parallel to the backs of the drawers, each of said brackets having a bearing slot internally thereof adapted for cooperation with the

said horizontal arm of said locking bar for maintaining said arm and said bar in a vertical plane for sliding horizontally into and out of drawer locking position, means whereby said bar locks said drawers in the locking position of said bar, and means for locking said bar against movement from said locking position.

4. In the combination of claim 1, a spring secured between said locking bar and one of said brackets for urging said locking bar out of said one position and into release position.

5. In the combination of claim 2, a spring secured between said locking bar and one of said brackets for urging said locking bar out of said one position and into release position.

6. In a combination of the class described, a cabinet housing having a series of sliding drawers, partitions between said drawers, a series of brackets supported on one of said partitions, each of said brackets having a bearing slot internally thereof and a constricted entrance into said bearing slot, a locking bar having a horizontal arm, said horizontal arm entering said bearing slots through said constricted entrances and thereafter maintained in said bearing slots for horizontal sliding movement, the plane of said sliding movement being juxtaposed to the plane of the backs of said drawers, hook-like portions on said drawers cooperable with surfaces of said locking bar

30 in one position of said bar to lock the drawers against outward movement, and means for locking said bar against movement from said one position.

7. In a combination of the class described, a cabinet housing having a series of sliding drawers, partitions between said drawers, a series of brackets having flanges whereby to be secured on one of said partitions with a portion of each of said brackets extending vertically from said partition, each of said bracket portions having a bearing slot internally thereof and a constricted entrance into said bearing slot, a locking bar having a horizontal arm, said horizontal arm entering said bearing slots through said constricted entrances and thereafter maintained in said bearing slots for horizontal sliding movement, the plane of said sliding movement being juxtaposed to the plane of the backs of said drawers, hook-like portions on said drawers cooperable with surfaces of said locking bar in one position of said bar to lock the drawers against outward movement, and means for locking said bar against movement from said one position.

JAMES C. SIEGEL.
